UNITED STATES PATENT OFFICE.

LOUIS JOSEPH ANTON STANIEWICZ, OF CHATHAM, CANADA.

BOOKBINDER'S CLAMP.

SPECIFICATION forming part of Letters Patent No. 703,495, dated July 1, 1902.

Application filed December 11, 1901. Serial No. 85,483. (No model.)

To all whom it may concern:

Be it known that I, LOUIS JOSEPH ANTON STANIEWICZ, bookbinder, of the city of Chatham, in the county of Kent, in the Province of Ontario, Canada, have invented certain new and useful Improvements in Bookbinders' Clamps, as hereinafter more particularly explained.

My invention relates to improvements in adjustable clamps or clamp-stands for holding books during embossing and gilding, &c.; and the object of the invention is to devise a simple clamp-stand whereby a book may be tilted or swung horizontally into a convenient position for the workman to emboss, gild, or otherwise decorate or work upon it; and it consists, essentially, of a stationary base arc-shaped in cross-section, a rocking base also arc-shaped in cross-section and designed to rock upon the stationary base, such stationary base being designed to be changed in position or swung horizontally and held stationary while in use and the rocking base being provided with clamping-bars between which the book is held, the clamping-bars and clamps being suitably secured to the top of the rocking base and such rocking base being provided with a central spring connection to the floor and the parts being otherwise arranged and constructed in accordance with my invention.

Figure 1 is a perspective view of my clamp-stand, showing it placed on a table and exemplifying the applicability of my invention. Fig. 2 is a cross-section. Fig. 3 is a detail of the base-board. Fig. 4 is an inverted detail of the stationary base or base normally held stationary. Fig. 5 is a detail of the rocking base. Fig. 6 is a detail of the ball-bearing through which the flexible cord extends which connects the rocking base to the stationary base. Fig. 7 is a detail of the tension-spring for the flexible cord and the device for varying the tension of the same.

In the drawings like letters of reference indicate corresponding parts in each figure.

A is a table of any ordinary construction, upon which my device is placed.

B is the base, which is provided with a central ring b, held in a circular opening in the same and in the center of which is a hole b'.

C is the base, which is ordinarily held sta-

tionary and provided with an annular plate c, which fits within the ring b when the base is placed in position.

D is a spring-plunger which extends through a hole in the top of the table and a hole b' in the base B into a hole c' in the base. The plunger D is provided with an annular projection d, between which and the enlarged hole through which the plunger extends fits the spiral spring d' in order to hold the plunger in the hole c' in the base C.

It will be noticed that the stationary base C is arc-shaped in cross-section and provided with end grooves c², provided with rubber strips, as indicated.

E is the rocking base, which is provided with a central hole e, a cross dovetail-shaped groove e', in the center of which is located the ball-bearing e², comprising the rings e³ and e⁴ and balls e⁵ and beads e⁶, provided with suitable rubber strips e⁷, designed to enter the corresponding grooves in the stationary base C.

F is a cord which extends through the holes e, being suitably knotted at the top above the ball-bearing e², the holes c and b' to the spiral spring G, which is connected at the top to the triangle g, as indicated.

g' is a bracket provided with a depending hook g², and g³ is a thumb-screw which extends through the upper member of the bracket and the base of the triangle.

By means of the thumb-screw g³ the tension of the spring G may be varied—that is to say, the tightness by which the rocking base E is held upon the stationary base C may also consequently be varied.

H H' are clamping-bars, between which the book I is held, the back of the book being placed uppermost. The bars H and H' are provided with tongues h and h', which fit into the groove e' and are designed to have longitudinal movement therein.

J is a clamping-screw which extends through the bars H and H' and the tongue h against the base of the groove e', this clamping-screw being designed to hold the clamping-bars in position when placed centrally crosswise of the rocking base E.

K represents ordinary clamping-screws, which extend through the end pieces k², attached to or forming part of the clamping-bars H.

75

100

By loosening the clamping-screws the book may be removed. Such screws are preferably provided with right and left hand threads meeting at the center, so that by turning the screws the bars move apart in order that the book may be quickly released.

Having now described the principal parts involved in my invention, I have briefly to state and it will be readily seen that the book may be tilted over laterally into a position convenient for the workman, so that he can emboss and burnish without any strain and with a perfect rest for himself upon the book or part of the frame. He also may, if desired, where the work requires release the plunger D and turn the whole device around horizontally to any desired position and work on it in that position either at right angles or otherwise to the position shown in the drawings.

20 The spring G and cord F, it will be readily seen, allow of the base E to rock upon the base C with facility, and yet connect them securely together. Should it be desired to hold the bases C and E stationary, I provide 25 end bolts or pins L, which fit into brackets l and l' on the bases C and E, respectively. The bolts or pins L are of course withdrawn should it be desired to allow the bases to rock one upon the other, so as to tilt the book into 30 any convenient position desired.

What I claim as my invention is—

1. The combination with the stationary base provided with a curved or arc-shaped top, of the rocking base provided with a curved or 35 arc-shaped bottom designed to rest upon the arc-shaped top, the clamping-bars secured on the rocking base and designed to receive between them the book to be embossed, means for holding such bars together to grip the 40 book and means for connecting the bases together, so as to permit of a rocking lateral movement as and for the purpose specified.

2. The combination with the stationary base provided with a curved or arc-shaped top, 45 of the rocking base provided with a curved or arc-shaped bottom designed to rest upon the arc-shaped top, the clamping-bars secured on the rocking base and designed to receive between them the book to be embossed, the hand- 50 screw extending through the ends of the bars and means for connecting the bases together, so as to permit of a rocking lateral movement as and for the purpose specified.

3. The combination with the stationary 55 base provided with a curved or arc-shaped top, of the rocking base provided with a curved or arc-shaped bottom designed to rest upon the arc-shaped top, the clamping-bars secured on the rocking base and designed to receive be- 60 tween them the book to be embossed, the hand-

screw extending through the ends of the bars, the said rocking bar being provided with a cross-groove, a hand-screw extending through the clamping-bar into and against the bottom of such groove and means for connecting the bases together so as to permit of a rocking lateral movement as and for the purpose specified.

4. The combination with the stationary base provided with a curved or arc-shaped top, 70 of the rocking base provided with a curved or arc-shaped bottom designed to rest upon the arc-shaped top, the clamping-bars secured on the rocking base and designed to receive between them the book to be embossed, means 75 for holding such bars together to grip the book, a cord extending through holes in the bases and spring means located intermediate of the length of the cord for allowing it to give and a suitable fastening for the bottom end 80 of the cord as and for the purpose specified.

5. The combination with the stationary base provided with a curved or arc-shaped top, 85 of the rocking base provided with a curved or arc-shaped bottom designed to rest upon the arc-shaped top, the clamping-bars secured on the rocking base and designed to receive between them the book to be embossed, means for holding such bars together to grip the book, a flexible cord extending through the 90 central holes in the bases, the spring located at the lower end, the triangle connected to the lower end of the spring, a bracket and hook connected to the floor and a thumb-screw extending through the upper end of the bracket 95 and into the triangle as and for the purpose specified.

6. The combination with the top rocking base and the clamps carried thereby for holding the book in place, of the bottom base and bottom base-board, said top and bottom bases having central holes, the cord extending through the central holes in both bases and the central bearing between the bottom base and base-board and a spring-plunger designed 105 to extend through the base-board into a hole in the bottom base as and for the purpose specified.

7. The combination with the curved rocking base, of the curved stationary base of the 110 clamps carried by the rocking base, the cord extending through the center holes of said bases, and the ball-bearings in which the top of the cord is fastened and which permits of the horizontal rotation of the bases without 115 twisting as and for the purpose specified.
